(57) **CLAIM**

The ornamental design for a pneumatic compactor front cover, as shown and described.

DESCRIPTION

FIG. 1 is a front view of a pneumatic compactor front cover showing our new design.

FIG. 2 is a left front view thereof.

FIG. 3 is a left side view thereof.

FIG. 4 is a rear left view thereof; and,

FIG. 5 is a top view thereof.

The broken lines shown are included for the purpose of illustrating environmental structures and form no part of the claimed design.

1 Claim, 5 Drawing Sheets

FIG. 1**FIG. 2****FIG. 3**

FIG. 4**FIG. 5**
